UNITED STATES PATENT OFFICE.

NATHAN H. DAVIS, OF PHILADELPHIA, PENNSYLVANIA.

DUST-GUARD FOR CAR-AXLE BOXES.

SPECIFICATION forming part of Letters Patent No. 519,152, dated May 1, 1894.

Application filed May 12, 1892. Serial No. 432,705. (No model.)

To all whom it may concern:

Be it known that I, NATHAN H. DAVIS, a citizen of the United States, residing in the city and county of Philadelphia, State of Pennsylvania, have invented a new and useful Improvement in Dust-Guards for Car-Axle Boxes, which improvement is fully set forth in the following specification and accompanying drawings.

10 My invention consists of a novel dust guard for a car axle box, formed of a plate with lining, as hereinafter described.

It further consists of the combination and arrangement of parts hereinafter set forth.

15 Figure 1 represents a vertical section of a dust guard embodying my invention. Fig. 2 represents a face view thereof, partly broken away, including a section of the box on line x, x , Fig. 1.

20 Similar letters of reference indicate corresponding parts in the two figures.

Referring to the drawings: A designates a portion of a car axle box of well known construction. In the rear of the box is a vertical chamber B, the walls of which have enlarged openings C for the passage of the axle or journal, as also well known, said chamber being open at top. In said chamber, is a dust guard consisting of a plate D of metal 25 or other suitable material, with a central opening slightly larger than the axle or journal, which passes freely through it, and a flange E around its edge. Around the central opening of the plate is a flange F, whose inner face is lined with a ring F' of steel, Babbitt or other metal, with which the axle or journal is directly in contact, said ring being properly secured to said flange F. To the side of the plate, contiguous to the wall 30 of the box, is secured a facing G of canvas or other fabric, which is held in contact with said wall by the action of a spring H, which consists of the curved or bent legs J, and the cross piece K, which joins the same, said legs bearing respectively against the plate D, and 35 the opposite wall of the chamber B, and thus preventing the usual rising and falling motions 40 of the box, it being seen that dust, dirt, &c., are prevented from passing between the rear

wall of the chamber and the facing G, and between the lining F and axle or journal, while leakage of oil from the box is also prevented. As the axle or journal is in contact 55 with the ring F', it runs with but slight friction on the dust guard, and as said lining is of durable nature, it does not wear out rapidly, and thus remains serviceable for a long time, said lining furthermore thickening or 60 increasing the wearing surface of the guard plate with which the axle is in contact, and upon which it rotates, it being evident that the flange and ring may be formed of one 65 piece of material.

The flange E of the plate D prevents displacement of the spring H, but as the plate D is considerably thinner than the space formed by the chamber in the longitudinal direction of the axle, and said chamber is open at top, 70 the spring may be drawn out from under the flange E, and then raised through the open top of the chamber, whereby it may be entirely displaced when so required.

It is evident that the spring may be restored to position through the open top of the chamber and engage under the flange, whereby it is again operative to hold the plate properly against the relative wall of the chamber B. It is also evident that the flange 80 E of the plate D, serves to stiffen said plate around the edges thereof, and that as said plate is thin and therefore flexible, it will adapt itself under pressure of the spring to any curved or irregular surface of the box. 85 Again, as said plate is formed of metal, it will not burn-out as is the case where plates of the class are constructed of wood, as heretofore practiced.

In order to secure the facing G to the plate 90 D, the flanged edges of the latter are formed by bending the said edges so as to form channels D', the ends of said facing are extended into said channels and clamped by the same, thus firmly connecting said ends with the 95 plate.

Having thus described my invention, what I claim as new, and desire to secure by Letters Patent, is—

1. A car axle box having a chamber, a plate 100 in said chamber with a central opening and a flanged rim, said opening having a flanged

wall, a metal ring lining said flanged wall, and a spring bearing against said flanged rim and one of the walls of said chamber, said parts being combined substantially as described.

2. A dust guard for a car axle box, consisting of a plate having a flange around the opening therein, in which the car axle rotates, and provided with a flanged rim, a canvas facing with its edges in said rim, and a spring adapted to bear against said flanged

rim and the wall of the chamber of the axle box in which the guard is located, said parts being combined substantially as described.

3. The plate of a dust guard having channeled edges, and the ends of the facing of said plate entering the channels, and clamped by the same, substantially as described.

NATHAN H. DAVIS.
